UNITED STATES PATENT OFFICE

146,784

DESIGN FOR A COMBINATION ARTICLE CARRYING AND DISPLAY DEVICE

Leon H. Best, Galva, Ill., assignor to John H.
Best & Sons, Inc., Galva, Ill., a corporation of
Illinois

Application January 12, 1946, Serial No. 125,490

Term of patent 14 years

(Cl. D14—3)

To all whom it may concern:

Be it known that I, Leon H. Best, a citizen of the United States, residing at Galva, in the county of Henry and State of Illinois, have invented a new, original, and ornamental Design for a Combination Article Carrying and Display Device, of which the following is a specification, reference being made to the accompanying drawing, forming a part thereof in which

Fig. 1 is a perspective view of a combination article carrying and display device embodying my new design showing the same in upright position; and

Fig. 2 is a perspective view of the same showing the device in horizontal position.

The characteristic features of my design are shown in full lines in the drawings.

I claim:

The ornamental design for a combination article carrying and display device, substantially as shown and described.

LEON H. BEST.
